UNITED STATES PATENT OFFICE.

THOMAS CORSCADEN, OF NEW BRITAIN, CONNECTICUT, ASSIGNOR TO THE
STANLEY WORKS, OF SAME PLACE.

DESIGN FOR A BRACE FOR SHELF-BRACKETS.

SPECIFICATION forming part of Design No. 24,517, dated July 30, 1895.

Application filed December 13, 1894. Serial No. 531,727. Term of patent 14 years.

To all whom it may concern:

Be it known that I, THOMAS CORSCADEN, a citizen of the United States, residing at New Britain, in the county of Hartford and State of Connecticut, have invented and produced a new and original Design for a Brace for Shelf-Brackets, of which the following is a specification, reference being had to the accompanying drawings, forming part thereof, 10 in which—

Figure 1 is a side view of a brace for a shelf-bracket, showing my design. Fig. 2 is a transverse sectional view of the same.

A is the body of the brace with parallel and 15 curved longitudinal edges, each end 3 extending obliquely to the length of said body on lines which are at right angles to each other

and with an angular extension 4 projecting beyond each of said ends 3.

The body of the brace is provided with longitudinal beads 5 and concavity 6 on one side and a bead 7 and concavity 8 on the opposite side, the concavity on each side being directly opposite the bead. The bead and concavity that come nearest the convex edge of the body 20 25 of the brace are shorter than the other bead and concavity.

What I claim is—

The design for a brace for a shelf bracket substantially as shown and described.

THOMAS CORSCADEN.
